CLAIM

The ornamental design for a removable fastener, as shown and described.

DESCRIPTION

FIG. 1 is a front perspective view of a removable fastener showing my new design;

FIG. 2 is a left side view, the right side being a mirror image thereof;

FIG. 3 is a bottom view thereof;

FIG. 4 is a top view thereof;

FIG. 5 is a rear view thereof; and,

FIG. 6 is a front view thereof.

The broken line showing of the nail in FIG. 2 is for illustrative purposes only and forms no part of the claimed design.
